Fig. 2

Fig. 3

FIG. 4

FIG. 5

FIGURE 1 is a front perspective view of a combined light for stage and advertising use and control unit therefor embodying my new design.

FIGURE 2 is a front elevational view thereof.

FIGURE 3 is a rear elevational view thereof.

FIGURE 4 is a top plan view thereof.

FIGURE 5 is an elevational view of one side thereof.

FIGURE 6 is an elevational view of the side opposite that shown in FIGURE 5.

FIGURE 7 is a bottom plan view thereof.

The dominant features of my design reside in the portions shown in full lines.

I claim:

The ornamental design for a combined light for stage and advertising use and control unit therefor, substantially as shown and described.
